UNITED STATES PATENT OFFICE.

WALTER A. BOCKIUS, OF WILMETTE, ILLINOIS.

LAP FOR CYLINDERS.

1,318,531.

Specification of Letters Patent. Patented Oct. 14, 1919.

Application filed November 8, 1916. Serial No. 130,118.

To all whom it may concern:

Be it known that I, WALTER A. BOCKIUS, a citizen of the United States, and a resident of Wilmette, in the county of Cook and State of Illinois, have invented certain new and useful Improvements in Laps for Cylinders, of which the following is a full, clear, and exact description.

The invention relates to laps for polishing engine cylinders and other cylindrical surfaces. It is now common practice to employ a lap in which a head is provided with spring pressed bars for engaging the cylinder, the springs acting on the bars to exert a pressure upon the bars so that the abrading or polishing material on the lap will act upon the cylinder.

One object of the invention is to provide an improved lap in which the use of spring pressed bars or a separate spring is dispensed with and in which a cylindrical body is utilized to apply the abrasive, so that substantially the entire peripheral surface of the body will be simultaneously active when it is operated in a cylinder.

A further object of the invention is to provide a lap which is simple in construction and can be produced at a low cost.

The invention consists in the several novel features hereinafter set forth and more particularly defined by claims at the conclusion hereof.

In the drawings: Figure 1 is a side elevation of the improved lap. Fig. 2 is a longitudinal section, the shank being shown in elevation. Fig. 3 is a plan, the shank being shown in section. Fig. 4 is a development of the periphery of the body of the lap showing the grooves therein for the abrading or polishing material.

The improved lap comprises a one-piece body comprising a rim 5, a hub 6, an arm 7 connecting the rim and the hub, and a strengthening rib 8, all integrally formed of a casting of suitable metal. A shank 9 for rotating the lap is removably connected to the hub 6 by a screw-threaded portion 10. The upper end of the shank is tapered, as at 11, so that it may be secured into the chuck of a drill press or other suitable machine for imparting rotation to the shank. A shoulder 12 of the shank abuts against the upper end of the hub 6. This shoulder and the screw-thread adapt the shank for connection to any of a series of laps of different

diameters. In practice, it is customary to have an equipment consisting of different sizes of bodies for bores of different diameters and by providing a detachable connection between the hub 6 and the shank 9, the laps may be readily and speedily interchanged for cylinders of different diameters.

In making the one-piece body, it is cast somewhat larger than the bore of the cylinder which it is adapted to polish or grind and then a section of the rim is slotted or cut away longitudinally, as indicated at 14 in Fig. 3, adjacent one side of the connecting arm 7. After the rim has been thus cut, it is placed in a clamp whereby it is contracted to the limits permitted by the slit and then turned in a lathe to the exact diameter desired for a given diameter of the cylinder. When the clamps have been removed, the elasticity of the rim will expand it to open the slot 14 and as a result it will form a body which is resilient and slightly larger in diameter than the diameter of the cylinder which it is adapted to polish or abrade. When the rim is forced into a cylinder of the size for which it is adapted, the rim will exert a substantially uniform yielding pressure against all portions of the cylinder wall around the rim. The slit 14 is cut through the rim adjacent that side of the arm 7 which is the front side during rotation, as indicated in Fig. 3, so that the resilient portion of the rim will be drawn around the cylinder instead of being pushed, because a pushing action might tend to operate the lap unevenly or bind in the cylinder. In practice, the shank 9 is rotated at the desired speed to cause the lap to rotate in the cylinder or other part to be polished or abraded. Helicoidal grooves 15 and 16 extend from the edges of the slit 14 around the periphery and oppositely helicoidal grooves 17 and 18 are formed in the periphery of the rim and cross the grooves 15 and 16. In practice, grease with suitable grinding powder or material therein is smeared on the periphery of the rim and into the grooves before the lap is lowered into the cylinder 19. The helicoidal crossed grooves serve to distribute the grease and abrasive during rotation of the lap.

The invention exemplifies a lap in which spring bars are dispensed with and which is formed of one piece and with a resilient

rim, the entire peripheral area of which is operative in the cylinder during the operation of the lap. As a result, a cylinder can be quickly ground or polished. By forming 5 the lap in the manner described, it can be produced at a low cost. A series of laps may be interchangeably connected to the shank.

The invention is not to be understood as 10 restricted to the details set forth, since these may be modified within the scope of the appended claims, without departing from the spirit and scope of the invention.

Having thus described the invention, what 15 I claim as new and desire to secure by Letters Patent, is:

1. In a lap, the combination of a substantially cylindrical rim which is longitudinally split at one point and a rigid sup- 20 port for one portion of the rim and where- by it may be rotated, the rim being inher-

ently resilient and unsupported except by said support so that the remaining portions thereof will be free to be contracted by the work.

25

2. In a lap, the combination of a rim which is longitudinally split, a hub and a support between the hub and one point of the rim, said hub, support and one portion of the rim being integral, the rim being re- 30 silient and unsupported except by said support so that the remaining portions thereof will be free to be contracted by the work.

3. In a lap, the combination of a hub, an arm and a rim which is longitudinally split 35 at one point, the hub and rim being integral and the rim being rigidly supported at the arm and being inherently resilient so that portions remote from the arm are movable relatively to the portion directly connected 40 to the arm.

WALTER A. BOCKIUS.
